UNITED STATES PATENT OFFICE.

JOHN ZEBLEY, OF PHILADELPHIA, PENNSYLVANIA.

DESIGN FOR A FRINGE.

SPECIFICATION forming part of Design No. 16,308, dated September 29, 1885.

Application filed May 9, 1885. Term of patent 3½ years.

To all whom it may concern:

Be it known that I, JOHN ZEBLEY, of Philadelphia, in the county of Philadelphia, and in the State of Pennsylvania, have invented a certain new and ornamental Design for Fringe; and I do hereby declare that the following is a full, clear, and exact description thereof, reference being had to the accompanying drawings, in which—

10 Figure 1 shows a view in front elevation of a piece of loop-fringe with a heading made in accordance with my design, and Fig. 2 a sectional view of a piece of straight fringe with a heading in accordance with my design.

15 My invention is intended more especially for card-fringe, but is applicable for any fringe having a heading substantially like that of card-fringe.

20 Heretofore card-fringe has been made with a plain heading having loops or straight strands depending therefrom.

The leading feature of my design consists in a band of chenille laid on and along the heading and running with the pattern of such heading.

25 In the drawings, A designates the heading, and B the loops or strands depending there-

from. Along the heading, and running with the pattern thereof, is the raised band C, of any material, having thread-like filaments, as 30 does chenille. As shown, this band has the appearance of being divided up into lengths by breaks or depressions. Such breaks, depressions, or divisions occur at regular intervals.

35 Having thus described my invention, what I claim is—

1. The design for fringe, consisting of the raised band of thread-like filaments on the front of the heading and running with the 40 pattern thereof, as herein shown and described.

2. The design for fringe, consisting of the heading and the raised band thereon running with its pattern and divided up into lengths by breaks or depressions, as shown and de- 45 scribed.

In testimony that I claim the foregoing I have hereunto set my hand this 13th day of April, A. D. 1885.

JOHN ZEBLEY.
